UNITED STATES PATENT OFFICE.

CIPRIANO ANDRADE, JR., OF NEW YORK, N. Y.

HAND-REEFING BOOM.

Application filed October 5, 1927. Serial No. 224,049.

My invention relates to a hand reefing boom adapted to either reef or furl a sail on a boat by hand, more quickly and with better effect on the sail than in the prior art.

5 I attain this object by the mechanism illustrated in the accompanying drawings, in which:

Fig. 1 is a side view of my device; and Fig. 2 is a top sectional view thereof on the 10 lines 2—2 of Fig. 1.

Similar letters and numerals refer to similar parts throughout the several views.

A is the mast; B is the boom; B¹ is a space in boom B to allow said boom to move 15 upward or downward at its after end; C is the forward part of the gooseneck; C¹ is the circular forward end of gooseneck C; D is the after part of the gooseneck; D¹ is the straight after end of gooseneck D; E is a 20 flat circular element rotatable over C¹; E¹ is a straight piece integral with E; E² is a circular hand holder integral with E¹; E³ is a circular hand holder rotatable over E²; E⁵ is a keyway in E; F is a cleat fastened 25 to mast A under E²; G is a circular shaft going through mast A; G¹ is a straight element integral with G, and rotatable over D¹; G² is a flat top element integral with G¹; G³ is a flat bottom element integral with 30 G¹; G⁵ is a keyway in G; H is a circular shaft passing through elements G² and G³ and preferably rotatable therein; H¹ is an eye integral with H, to hold the lower forward end of the mainsail; K is a circular 35 element between G² and G³ and outside of H, and rotatable between G² and G³, and rotatable outside of H; K¹ is a square piece integral with K; K² is a circular element integral with K¹; M is a circular shaft in 40 side of K² and rotatable therewith; P are plates fastened to boom B by screws Q, plates P also holding the ends of circular shaft M; R is a nut, to hold circular shaft G from moving away from circular element 45 E; S are bolts to hold goosenecks C and D together tight over mast A; and T is a nut, to hold circular shaft H from moving away from G³. It will be understood that a key will be set in keyways E⁵ and G⁵.

50 The operation of my device is as follows:

Let us assume that the mainsail has been fully wound around the boom B, and that it is desired to raise the mainsail. All that is necessary to do is to pull the mainsail up by the usual sail halyard; and as the sail goes up, the boom B can freely rotate with

elements M, K², K¹, K, H, T, H¹, G³, G², G¹, G, R, E, E¹, E² and E³. When the mainsail is at its full height, and the hand holder E³ is in the position shown in Fig. 1 60 hereof the halyard should be fastened on cleat F and also on hand holder E³, so that said hand holder E³ cannot rotate, which will hold the boom B in nonrotatable position. 65

Let us now assume that when the mainsail is thus set at its full height, it is then desired to reef it. All that is necessary, is to take the halyard off of cleat F and hand holder E³, and then rotate E³ by hand in either direction, which will rotate boom B, and wind the mainsail on boom B. As soon as the mainsail is wound as far down as necessary on boom B, the hand holder E³ should then be set in the position shown in 75 Fig. 1 hereof and the halyard should then be fastened on cleat F and also on hand holder E³, which as stated will prevent the boom B from rotating.

If it is then desired to entirely furl the 80 mainsail, all that is necessary is to take the halyard off of cleat F and hand holder E³, and then further rotate E³ by hand until the mainsail is entirely furled on boom B. Then the hand holder E³ should be set in the position shown in Fig. 1 hereof, and the halyard should again be fastened on cleat F and also on hand holder E³, so that boom B cannot 85 rotate.

It will be further noted that in my device, 90 the elements H and K permit the boom B to move sideways as far as desired at its after end; and the elements M and K² permit the boom B to move up or down as far as desired at its after end. It will be noted 95 that the sideway movement of the boom at its outer end can be accomplished if H is fastened tight to G² or to G³ or to both G² and G³, and K is rotatable about H. And also the sideway movement of the boom at 100 its outer end can be accomplished if H is fastened tight to K, and H is rotatable through G² and G³. And also the sideway movement of the boom at its outer end can be accomplished if H is rotatable through 105 G² or G³, or through G² and G³, and K is also rotatable about H. And it will be further noted that the up or down movement of the boom at its outer end can be accomplished if M is fastened tight to either one 110 or both of plates P, and K² is rotatable about M. And also the up or down move-

ment of the boom at its outer end can be accomplished if M is fastened tight to K², and M is rotatable through the two plates P. And also the up or down movement of the boom at its outer end can be accomplished if M is rotatable through one or both of the plates P, and K² is also rotatable about M.

The purpose of having E³ rotate over E² is to prevent E³ from causing friction on the hand of the man who is rotating E³, to rotate the boom B. Of course E³ could be eliminated, but this would cause some friction by E² against the hand of the man who was rotating E², to rotate boom B. And in the claims herein, the words "hand holder" will refer either to E², or to E² plus E³.

It will be further noted that the circular shaft H, being fastened at both ends in G² and G³, holds element K very firmly; and circular shaft M, being fastened at both ends in plates P, holds element K² very firmly. This makes it entirely safe for the upward pull of the mainsail on either side of the boom B, when the mainsail is reefed in heavy weather, and hand holder E³ is fastened by the halyard to cleat F.

It will of course be understood that my device can be used on a foresail, mizzensail, or any other form of sail.

30 The bolts S, shown in my Figs. 1 and 2, fasten my gooseneck C, D both above and

below my shaft G, and completely around the entire outer surface of my mast A, which makes it impossible for my mast A to break because of the cutting of my shaft G 35 through my mast A.

The gooseneck C, D will hold the mast A safely, so that the hole in mast A for the circular shaft G, will not cause any breakage of mast A.

As is well known in the art, any mechanical equivalent of my various parts herein shown are a part of my invention, and of the claims herein.

45 I claim:

1. In a hand reefing boom; a mast; a shaft located through said mast, said shaft being adapted to rotate said reefing boom; a gooseneck having a surface flat both vertical and sideway on the side of said mast opposite the reefing boom; a flat element fastened direct to said shaft, said flat element being also rotatable directly against said flat surface of the gooseneck; and a hand holder integral with and in alignment with said flat element.

2. In a hand reefing boom, a shaft located inside of said reefing boom, said hand reefing boom being rotatable sideway in relation to said shaft.

CIPRIANO ANDRADE, JR.
